Duell, Webfield & Bell
ATTORNEY

UNITED STATES PATENT OFFICE.

MORTON H. STARR, OF ST. JOHNSBURY, VERMONT, ASSIGNOR TO E. AND T. FAIRBANKS AND COMPANY, OF ST. JOHNSBURY, VERMONT, A CORPORATION OF VERMONT.

SCALE.

Application filed June 12, 1922. Serial No. 567,605.

To all whom it may concern:

Be it known that I, MORTON H. STARR, a citizen of the United States, residing at St. Johnsbury, in the county of Caledonia and State of Vermont, have invented certain new and useful Improvements in Scales, of which the following is a full, clear, and exact description, such as will enable others skilled in the art to which it appertains to make and use the same.

This invention relates to scales, and more particularly to an adjustable counterpoise or back balance ball for use on weigh-beams ordinarily employed in connection with high capacity scales.

It is an object of the invention to provide an improved balancing device of the class mentioned which is relatively simple in construction, and reliable and exact in function under all conditions of service.

Another object is the provision of an improved adjusting mechanism for the balance ball with locking mechanism therefor for securing the balance ball in adjusted position.

Other objects will be in part obvious in connection with the following detailed description of an illustrative embodiment of the invention and in part pointed out hereinafter.

The invention accordingly consists of features of construction, combination of elements, and arrangements of parts, which will be exemplified in the construction hereinafter set forth, and the scope of the application of which will be indicated in the appended claims.

In the accompanying drawings wherein a typical preferred embodiment of the invention is disclosed,

Fig. 1 is a side elevation of a weigh-beam equipped with the invention;

Fig. 2 is a central vertical longitudinal sectional view on an enlarged scale;

Fig. 3 is a rear end elevation; and

Fig. 4 is a transverse, sectional view taken approximately on the line 4—4 of Fig. 2 looking in the direction of the arrows.

This invention is disclosed in prior pending application for scales, Serial No. 441,544 filed February 1, 1921, and the present application is a division of said prior application.

Referring now to the drawing for a detailed description of the embodiment there shown the weigh-beam 1 is supported upon a beam stand 2 attached to the upper surface of a beam shelf (not shown) and carries an adjustable poise 3 mounted for longitudinal adjustment along the weigh-beam. The weigh-beam is substantially channel shaped in cross section having downwardly extending flanges or side walls, presenting a downwardly facing channel opening. The beam stand 2 extends into the channel opening and carries spaced bearings 4 contacting in supporting relation with knife-edge bearing 5 carried by the spaced walls of the weigh-beam, the latter being thus supported for pivotal movement on said bearings. A power transmission rod 6 extends from its connection with scale levers (not shown) to a connecting block 7 supported on knife-edge bearings 8 carried by the walls of the weigh-beam.

A back balance poise (not shown) is preferably suspended from the rear end portion of the beam by means of a rod 9 connected to a yoke 10, the latter being substantially U-shaped, disposed centrally of the beam walls and having spaced bearing blocks 11 pivotally supported by bearings 12 mounted in the walls of the weigh-beam. The walls are preferably apertured for this purpose. The vertically disposed legs 13 of the yoke 10 are outwardly turned at 14 forming supports for the bearings 11, and the walls of the beam are thickened at 15 providing ample supporting area for the lower bearing members 12. It will be seen that the stresses incident to the counterpoise weight are transmitted equally to the opposite walls of the weigh-beam, the resulting stress being in the central vertical plane. As will be understood, counterpoise weights are added or subtracted from the counterpoise rod until the excess or deficiency in the balanced condition is within the range of the balancing power of the precise adjustment provided by an adjustable balance ball more fully hereinafter described.

Means for completing the precise balancing of the beam in zero or no load position is provided by a balance ball 16 movable longitudinally to adjust the center of gravity

of the beam relatively to its points of support. A shaft 17 threaded to said ball is rotatably mounted in a frame or bracket 18 providing a housing for the ball and being 5 adjustably supported by bolts 19 passing through slots 20 in the end wall 21 of the beam, the frame being disposed between the side walls of the beam which provide a housing therefor, and the ball being restrained from rotation in said frame through 10 the intermediary of adjustable pins 22 carried by the ball or bracket. The bracket 18 is provided with upper and lower walls and an integral rear wall 23 having a vertical 15 slot 24 on its outer surface. Pins 25 are mounted in the rear beam wall 21 extending into said vertical slot for guiding vertical movement of said bracket and aiding in positioning it. The pins 25 are held in 20 position by a cover plate 26 overlying the outer surface of rear wall 21 and secured in position by the bolts 19 passing therethrough. A spacing and supporting sleeve 27 on the shaft 17 abuts at its opposite 25 ends with the cover plate 26 and rear bracket wall 23.

The shaft 17 extends through the end wall of the beam and is provided at its outer end with an operating hand wheel 28. The 30 shaft is also centrally recessed for the reception of a longitudinally movable lock-releasing push pin 29. This releasing pin carries at its outer end an operating button 30 disposed concentrically with respect to operating wheel 28 and adapted to be pressed by a thumb or finger of the operator's hand, the same hand being employed to simultaneously turn the hand wheel. Pin 29 is connected at its inner end with a double ended 40 locking pawl or pinion dog 31 having laterally disposed teeth 32 at both ends thereof, and being disposed in a slot 33 through the operating shaft 17 and pressed into engagement with a toothed circular locking plate 45 or pinion 34 by means of a spring 35 and follower 36 disposed in said central recess. The locking plate 34 is secured to the rear wall of the bracket 18 and is arranged concentrically with rod 17 whereby its locking 50 teeth are engageable by the locking pawl in any angular position of the latter.

The bracket 18 carrying the balance ball 16 may be adjusted into proper position within the housing provided by the weigh-beam and secured there through the agency 55 of the bolts 19 and slots 20, the adjusting movement being guided by the pins 25 engaging in the vertical slot 24. The beam may be approximately balanced by the adjusting weights supported by the yoke 10, and a precise balance is reached by the fine 60 adjustment provided by the balance ball 16 and the exact adjusting device therefor as described. When a precise balance is 65 reached the balance ball is automatically

locked in adjusted position through the agency of the spring 35 and locking pawl 31 when pressure upon the button 30 is released so as to prevent accidental displacement.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. In combination, a weigh-beam having a housing, a balancing device for said beam including a ball carried in said housing, and means for adjusting said ball laterally and longitudinally with reference to said weigh-beam.

2. In combination, a weigh-beam having a housing, a balancing device for said beam including a ball carried in said housing, an adjusting rod for said ball extending into said housing, and means for operating said adjusting rod to effect adjustment of said ball.

3. In combination, a weigh-beam having a housing, a balancing device for said beam including a ball carried in said housing, an adjusting rod for said ball extending into said housing, and manually controlled locking means for said rod.

4. In combination, a weigh-beam having a housing, a balancing device for said beam including a ball carried in said housing, an adjusting rod for said ball, locking means for said rod normally pressed into locking position, and a manually operated pin concentric with said rod for releasing said locking means.

5. In combination, a weigh-beam having a housing, a bracket secured within said housing and a balancing ball adjustably carried by said bracket.

6. In combination, a weigh-beam having a housing, a bracket secured within said housing, a balancing ball adjustably carried by said bracket, means for adjusting said ball, and manually controlled locking means for said adjusting means.

7. In combination, a weigh-beam, a balancing ball for said beam mounted thereon, means for adjusting said ball to balance said weigh-beam, locking means for said

- adjusting means normally urged to locking position, and manual means for releasing said locking means.
8. In combination, a weigh-beam, a balancing ball for said beam mounted thereon, means for adjusting said ball to balance said weigh-beam, locking means for said adjusting means normally urged to locking position, and manual means for releasing said locking means disposed adjacent said adjusting means for simultaneous operating therewith by a single hand of the operator.
9. In combination, a weigh-beam having spaced walls, a counter poise, and means for connecting said counter poise to said beam including spaced pivotal bearings supported in said wall.
10. In a scale, in combination, a channel shaped weigh-beam having downwardly extending flanges or side walls, a balance ball bracket secured in the channel of said weigh-beam between said walls, and a balance ball adjustably mounted in said bracket.
11. In a scale, in combination, a channel shaped weigh-beam having downwardly extending flanges or side walls, a bracket adjustably secured within the channel of said weigh-beam between said walls, a balance ball adjustably mounted in said bracket, means for adjusting said balance ball for varying the center of gravity of said weigh-beam with respect to its supports, and a locking mechanism for locking said ball in adjusted position.
12. In a scale, in combination, a channel shaped weigh-beam having downwardly extending flanges or side walls and a transverse wall extending therebetween, a balance ball bracket adjustably secured to said transverse wall within the channel of said weigh-beam, a balance ball adjustably mounted in said bracket, means for adjusting said balance ball to vary the center of gravity of said weigh-beam with respect to its supports, and locking mechanism for locking said ball in adjusted position.
13. In a scale, in combination, a weigh-beam, a balance ball for said weigh-beam, means for adjusting said balance ball for varying the center of gravity of said weigh-beam with respect to its supports, a locking plate carried by said weigh-beam and lying adjacent said adjusting means, and a locking pawl controlled by said adjusting means and adapted to engage said locking plate to lock said balance ball in any adjusted position.
14. In a scale, in combination, a weigh-beam, a balance ball for said weigh-beam, a rotatable shaft having threaded engagement with said balance ball for adjusting the same to balance said weigh-beam, operating means for said shaft, a circular locking plate carried by said weigh-beam and lying adjacent said shaft, a locking pawl controlled by said operating means and adapted to engage said locking plate to lock said balance ball in any adjacent position, and a push rod concentric with said adjusting shaft for releasing said locking pawl.
15. In a scale, in combination, a channel shaped weigh-beam having downwardly extending flanges or side walls, a balance ball mounted in the channel of said weigh-beam adjacent said walls and being adjustable therein, and a U-shaped yoke for an additional balancing weight pivoted to the walls of said weigh-beam and spanning said balance ball.
16. In a scale, in combination, a weigh-beam, a balance ball bracket for said weigh-beam, a balance ball carried by said bracket, and means for adjustably connecting said bracket to said weigh-beam.
17. In a scale, in combination, a weigh-beam, a balance ball bracket for said weigh-beam, a balance ball carried by said bracket, means for securing said bracket to a wall of said weigh-beam for vertical adjustment, and means carried by said wall for guiding said adjustment.
18. In a scale, in combination, a weigh-beam, a balance ball for said weigh-beam, means for adjusting said balance ball for balancing said weigh-beam, means for locking said balance ball in adjusted position, means associated with said adjusting means for operating said locking means, and means whereby said locking means is automatically moved to locking position following an operation of said adjusting means.
19. In combination, a weigh-beam having spaced walls, a balance ball supported between said walls, a counterpoise, and a U-shaped yoke for supporting said counterpoise spanning said balance ball, and having spaced pivotal connection with said walls.
- In testimony whereof I affix my signature, in the presence of two witnesses.
